(57) **CLAIM**

The ornamental design for a wall support for a television set, as shown and described.

DESCRIPTION

FIG. 1 is a top, front and side perspective view of a first embodiment of a wall support for a television set, showing our new design;

FIG. 2 is a front perspective view thereof;

FIG. 3 is a perspective view thereof from the left of FIG. 2; FIG. 4 is a side perspective view thereof from the right of FIG. 2;

FIG. 5 is a rear perspective view thereof;

FIG. 6 is a top perspective view thereof;

FIG. 7 is a bottom perspective view thereof;

FIG. 8 is a front and top perspective view thereof;

FIG. 9 is a front, bottom and side perspective view thereof;

FIG. 10 is a top, front and side perspective view of a second embodiment of a wall support for a television set, showing our new design;

FIG. 11 is a front perspective view thereof;

FIG. 12 is a perspective view thereof from the left of FIG. 11;

FIG. 13 is a perspective view thereof from the right of FIG. 11;

FIG. 14 is a rear perspective view thereof;

FIG. 15 is a top perspective view thereof;

FIG. 16 is a bottom perspective view thereof;

FIG. 17 is a front and top perspective view thereof; and,

FIG. 18 is a front, bottom and side perspective view thereof.
